UNITED STATES PATENT OFFICE.

BURT A. PETERSON, OF ROCKFORD, ILLINOIS, ASSIGNOR TO BARBER-COLMAN COMPANY, OF ROCKFORD, ILLINOIS, A CORPORATION OF ILLINOIS.

CREEL.

Application filed November 28, 1924. Serial No. 752,738.

Application Serial No. 190,501, filed September 10, 1917, by Howard D. Colman, (Patent No. 1,544,055 dated June 30, 1925), discloses a warping apparatus provided with an electric stop motion. The detectors are mounted on the creel and are arranged to close electric contacts included in the warper-controlling circuit. The creel comprises a plurality of bays adapted to receive removable yarn-mass-supporting devices. Each bay is provided at its outer side with a hinged gate on which the detectors are mounted, there being a detector for each cheese. The detectors for each vertical row of cheeses are mounted upon a support in the form of an upright square metallic tube. Associated with the detector are various thread-guiding plates which are secured to the metallic tube. The latter encloses an electric conductor with which contact is made when a thread breaks or becomes unduly slack.

The object of the present invention is to simplify and cheapen the construction of the upright support upon which the detectors and thread-guiding plates are mounted and in which the before-mentioned electric conductor is enclosed.

In the accompanying drawing, Figure 1 is a fragmental front elevation of one bay of a creel embodying the features of my invention.

Fig. 2 is a section on line 2—2 of Fig. 1.

Fig. 3 is a fragmental perspective view.

The particular embodiment herein shown of the invention is adapted to support yarn masses in the form of cheeses *a*. Each bay is arranged to support four vertical rows or columns of cheeses, the front of the bay is closed by means of a hinged gate 1.

The means for detecting exhaustion or excessive slackness of the yarn extending from the cheeses *a* to the warper (not shown) comprises detectors mounted upon the gate 1, there being a detector for each cheese. The detectors for each vertical row of cheeses are mounted upon an upright bar 2 forming part of the gate 1. As best shown in Fig. 2, each bar 2 consists of a wooden post 3 and a board 4 secured to one side of the post, the parts 3 and 4 forming an upright which is approximately square in cross-section. Preferably the rear and right-hand

sides of the bar 2 are covered with sheet metal 5 secured in place in any suitable way. 55

Each detector consists of an arm 6 preferably formed of a piece of wire bent into the form of a loop so as to provide two parallel portions against which the thread bears. These parallel portions are bent so as to form 60 notches 7 through which the thread may run. The tension of the thread normally holds the arm 6 in contact with a stop rod 8 against the action of gravity. At the side toward which the arm 6 tends to fall are two plates 65 9 and 10 against the edges 11 of which the thread is carried by the arm 6 if the thread becomes slack. 12 is a guide plate which is parallel with the plates 9 and 10. The upper portions of the plates 9 and 12 are secured together by the stop rod 8. The arm 6 extends above the plates 10 and 12. In the warper-replenishing operation the thread passes into operative relation to the detector by moving upward along the curved edge 75 13 of the plate 12, the edge 13 serving to guide the thread into the notch 7 of the adjacent portion of the arm 6. The rounded end of the plate 10 allows the thread to spring over the upper end of said plate into contact with 80 the sloping upper end of the arm 6, the thread being thus guided into the space between the arm 6 and the edges 11.

The plate 9 comprises an elongated base portion 14 of approximately the same width 85 as the upright 2. The plate 10 has a base flange 15 which is secured to the base portion 14 in a suitable way, as by electric welding. The plate 12 likewise has a base flange 16 which is secured to the base portion 14 by welding or in any other preferred way. 90

The detector arm 6 is provided with a pivot portion 17 which is mounted in a bearing 17^a in the base portion of the plate 9. 95

It will be seen that the plates 9, 10 and 12 and the detector 6 constitute a unit which may be readily mounted upon the upright 2 by means of screws 18 or other suitable means.

When a detector falls an electric circuit is closed by means to be now described. A contact arm 19 is attached to the pivot 17 of the arm 6 and is arranged to swing into contact with an electric conductor 20 extending longitudinally of and within the bar 2. 100 It will be noted that the post 3 has a groove 105

or channel 21 formed in its left-hand side, said groove extending from top to bottom of the bar and being closed by the board 4. The conductor 20 is located within said groove.

The left-hand side of the post 3 is cut away to form recesses 22 which communicate with the groove 21, there being one recess for each thread-guiding and detecting unit. 10 The recess is large enough to receive the inwardly projecting portion of the bearing 17^a and the contact arm 19, and is covered by the base plate 14.

It will be seen that the bar 2 serves to 15 enclose the contact arms 19 and the conductor 20 and thus keeps said parts free from dust and lint, thereby making it safe to use a current of sufficiently high voltage to ensure passage of the current between the 20 conductor 20 and the contact arm 19 of a fallen detector (see Fig. 2 and the detector 6^x of Fig. 1). No special means need be employed to insulate the conductor 20 from its support, inasmuch as the support consists of a wooden post. Moreover, the assembling of the parts is a very simple matter, as the groove 21 and board 4 hold the conductor 20 in proper position, and the unit formed of the parts 6, 8, 9, 10, 12, 14, 25 30 15, 16, 17^a and 19 may be quickly secured in place in proper relation to a given cheese. The conductors 20 of the several bars 2 are

connected into the circuit in any preferred manner.

I claim as my invention:

1. In a creel, an upright bar, a series of electric stop-motion detector units supported by said bar, said bar comprising a non-conducting post having a longitudinal groove in one side and a board covering said groove, 40 said post having in said side a series of recesses communicating with said groove, a conductor within said groove, each detector unit having a contact arm adapted to engage said conductor, each of said contact arms 45 lying within one of said recesses, each detector unit having a base plate secured to said post and closing one of said recesses, whereby said conductor and contact arms are completely enclosed. 50

2. In a creel, a bar, a series of electric stop-motion detectors supported by said bar, said bar being formed of non-conducting material and having a longitudinal channel therein and a series of recesses communicating with said channel, and a conductor within said channel, each detector having a contact portion adapted to engage said conductor, each of said contact portions being enclosed within one of said recesses. 55

In testimony whereof, I have hereunto affixed my signature.

BURT A. PETERSON
